Attorneys.

UNITED STATES PATENT OFFICE.

HUBERT WALKER, OF CLECKHEATON, ENGLAND.

APPARATUS FOR SCOURING, DYEING, OR OTHERWISE TREATING WITH LIQUOR,
WOOL, YARN, OR OTHER FIBEROUS MATERIAL.

1,354,081.

Specification of Letters Patent. Patented Sept. 28, 1920.

Application filed December 8, 1917. Serial No. 206,149.

To all whom it may concern:

Be it known that I, HUBERT WALKER, a subject of the King of Great Britain, residing at The Manor House, Cleckheaton, in the county of York, England, have invented certain new and useful Improvements in Apparatus for Scouring, Dyeing, or Otherwise Treating with Liquor, Wool, Yarn, or other Fibrous Material, of which the following is a specification.

This invention relates to apparatus for scouring, dyeing, or otherwise treating with liquor, wool, yarn, or other fibrous material and has for its chief object to cause the material that is passing through the machine to be subjected to a constant scouring action without being subjected to entanglements, such as might be caused by the rubbing together of two fibrous surfaces, such as two endless aprons, or sets of tapes running face to face which are sometimes employed for conveying fibrous material through machines of this class.

The invention consists in the combination of a perforated cylinder, or a series of perforated cylinders and a traveling apron so arranged as to act as a combined circulator and scourer and conveyer.

In the accompanying drawings, Figure 1 is an elevation and Fig. 2 a longitudinal section of the machine.

A, A indicated the perforated cylinders, B indicates the traveling apron and C indicates a tank for the scouring or other liquor.

In the example shown, a row of perforated cylinders A, A, are mounted in bearings in the tank C, the lower portions of the cylinders being submerged in the scouring or other liquor when the machine is in operation. These cylinders are conveniently driven from a main driving shaft D by chains b⁷, b⁸, b⁹, b¹⁰, with the exception of the cylinder at the feed end of the machine which is driven by the frictional contact of the endless apron or conveyer B. The latter passes over a feed roller b and between groups of rollers b¹ which retain it in contact with or in proximity to the under part of the cylinders A. The conveyer then travels over delivery rollers b² back to the feed roller b by way of guide rollers b³, b⁴. In the example shown the guide roller b⁴ is mounted on a shaft carried by a pair of levers such as b⁵ which can be moved to any

required position to regulate the tension of the conveyer and be retained in such position by inserting a pin in a perforated plate b⁶ that is mounted on the side of the tank. Passing around the center or intermediate portion of the cylinders A, A, and a guide roller a is an endless guide tape a¹ which guides the material under operation and keeps it in position upon the conveyer. One of the delivery rollers b² is situated in proximity to a pair of squeezing rollers E, E¹, to which the scoured or otherwise treated material is forwarded by the conveyer and delivery rollers. These squeezing rollers are driven by toothed wheels e¹ and the conveyer B is driven partly by a chain b¹¹ and partly by frictional contact with the cylinders A. Situated between the delivery roller b² and the squeezing rollers is a bar or plane e² which directs the material between the squeezing rollers. The perforated cylinders are fitted with internal mechanical devices whereby the inside of such cylinders may from time to time be flushed with liquor and so assist the scouring or treating of the material as it is passing through the machine. This is effected by fitting into the interior of such cylinders a number of troughs a², the arrangement being such that each trough when entering the liquor shall be charged with a certain amount of air which it releases in the process of rotation and thus serves to agitate the liquor by such air bubbling up through the perforations in the cylinder and through the liquor in the tank. Each trough having released the air contained therein becomes filled with the scouring or other liquid which is also discharged through the perforations in the cylinders in the process of rotation and continually agitates the liquor and thereby serves to assist in the scouring or otherwise treating of such material as may be passing between the cylinders and conveyer. The material is fed in at one end of the machine and transferred to the other end by the combined action of the cylinders and conveyer, the scouring liquid continually passing in and out through the perforated cylinders as they revolve and through the material under operation as such material passes between the perforated cylinders and the conveyer. Liquor that is squeezed out of the material falls into a trough e and is conveyed by a pipe c¹ to a compartment c² containing a

filter c^3 and a draw off pipe c^4 , the said liquor returning to the tank C through the filter and an aperture c^5 .

What I claim as my invention and desire 5 to secure by Letters Patent of the United States is:—

1. In apparatus for treating fibrous material with liquor, the combination of a receptacle adapted to contain liquor, a plurality of perforated cylinders arranged to be 10 rotated in a partly submerged condition in the liquor, each of said cylinders containing a number of troughs which during the rotation of the cylinders scoop up liquor 15 from the receptacle, discharge it through the perforations in the cylinder and convey air through the liquor in the receptacle, and a traveling apron arranged to travel in contact with the lower part of the cylinders.
2. In apparatus for treating fibrous material with liquor, the combination of a receptacle adapted to contain liquor, a plurality of perforated cylinders arranged to be 20 rotated in a partly submerged condition in the liquor, each of said cylinders containing a number of troughs which during the 25 rotation of the cylinders scoop up liquor from the receptacle, discharge it through the perforations in the cylinder, and convey 30 air through the liquor in the receptacle, an endless conveyer passing over feed and delivery rollers, under guide rollers and between groups of rollers arranged to cause the conveyer to travel in contact with the 35 lower part of the cylinders, a guide roller situated above one of the delivery rollers and an endless guide tape passing over such 40 guide roller and around the group of cylinders between their ends.
3. In apparatus for treating fibrous material with liquor, the combination of a receptacle adapted to contain liquor, a plurality of perforated cylinders arranged to be 45 rotated in a partly submerged condition in the liquor, each of said cylinders containing a number of troughs which during the rotation of the cylinders scoop up liquor from the receptacle, discharge it through the perforations in the cylinder and convey 50 air through the liquor in the receptacle, an endless conveyer passing over feed and delivery rollers, under guide rollers and between groups of rollers arranged to cause the conveyer to travel in contact with the lower part of the cylinders, a guide roller situated above one of the delivery rollers and an endless guide tape passing over such guide roller and around the group of cylinders between their ends, a pair of squeezing rollers situated in proximity to one of the delivery rollers and a plate arranged to direct the material delivered from the delivery rollers into the squeezing rollers.
4. In apparatus for treating fibrous material with liquor, the combination of a receptacle adapted to contain liquor, a plurality of perforated cylinders arranged to be 60 rotated in a partly submerged condition in the liquor, each of said cylinders containing a number of troughs which during the 65 rotation of the cylinders scoop up liquor from the receptacle, discharge it through the perforations in the cylinder and convey air through the liquor in the receptacle, an endless conveyer passing over feed and delivery rollers, under guide rollers and between groups of rollers arranged to cause the conveyer to travel in contact with the lower part of the cylinders, a guide roller situated above one of the delivery rollers and an endless guide tape passing over such 70 guide roller and around the group of cylinders between their ends, a pair of squeezing rollers situated in proximity to one of the delivery rollers and a plate arranged to direct the material delivered from the delivery rollers into the squeezing rollers, a trough situated underneath the squeezing rollers, a compartment situated at the feed end of the receptacle and connected with the 75 trough by a pipe, the said compartment containing a filtering device through which liquid can return to the receptacle, and an aperture for draining purposes.

In testimony whereof I affix my signature 80 in presence of two witnesses.

HUBERT WALKER.
